UNITED STATES PATENT OFFICE.

FRANK C. LORENCE, OF LARSON, NORTH DAKOTA.

DEVICE FOR PROTECTING AND FORCING PLANTS.

1,257,898.

Specification of Letters Patent. Patented Feb. 26, 1918.

Application filed June 5, 1917. Serial No. 172,984.

To all whom it may concern:

Be it known that I, FRANK C. LORENCE, a citizen of the United States, residing at Larson, in the county of Burke and State 5 of North Dakota, have invented new and useful Improvements in Devices for Protecting and Forcing Plants, of which the following is a specification.

This invention relates to devices for protecting and forcing plants and it has for its 10 object to produce a simple and improved device of this class which will be inexpensive in construction, efficient in use and which may be readily knocked down or taken apart 15 for convenience in shipment and storage.

A further object of the invention is to produce a device of this class including side members, a back member and a front member, the construction being such that back 20 and front members of different width may be used in connection with the side members, the latter being standardized.

A further object of the invention is to produce a device of this class which includes 25 a transparent front member that will admit the rays of the sun, the device being so light as to be easily moved about to the most advantageous position.

With these and other ends in view which 30 will readily appear as the nature of the invention is better understood, the same consists in the improved construction and novel arrangement and combination of parts which will be hereinafter fully described 35 and particularly pointed out in the claims.

In the accompanying drawing has been illustrated a simple and preferred form of the invention, it being, however, understood that no limitation is necessarily made to the 40 precise structural details therein exhibited, but that changes, alterations and modifications within the scope of the claims may be resorted to when desired.

In the drawing:

45 Figure 1 is a perspective view of a device constructed in accordance with the invention.

Fig. 2 is a top plan view of the same.

Fig. 3 is a sectional view taken on the 50 line 3—3 in Fig. 2.

Fig. 4 is a transverse sectional view taken on the line 4—4 in Fig. 2.

Fig. 5 is a detail view of the clip or clamp used in connection with the invention.

55 Corresponding parts in the several figures

of the drawing may be denoted by like characters of reference.

The improved plant protector comprises in its makeup two side walls or side members 15, a back member 16 and a front member 17, the latter being made of transparent material, preferably glass. The side walls 15, as well as the back member 16, are usually made of wood although other material such as indurated fiber may be substituted in the manufacture of either or all of said members. The side walls 15 are of triangular shape, each being bounded by the base 18, the rear edge 19 and the front edge 20. Each side member is provided adjacent to 70 the back edges 19 with a dove-tailed groove 21 running parallel to said back edge, and each side member is provided adjacent to the front edge 20 with a groove 22. The back member 16 is provided with dove-tailed 75 tongues 23 at the side edges thereof, said tongues engaging the dove-tailed grooves 21 in the side members which latter will thus be assembled together. The front member 17, consisting of a pane of glass of suitable 80 dimensions, will be supported in the grooves 22 adjacent to the front edges of the side members, and will be secured in position by a special clip or clamp 24, made of resilient 85 wire, said clamp being provided at the ends thereof with downturned arms 25, each having a terminal hook or prong 26 adapted to engage the outer faces of the side members as clearly seen in Figs. 1 and 4. The front edges of the side members will thus 90 be prevented from expanding and the glass will be held in position with sufficient security, but in a manner which will not interfere with its being slid or moved in an upward direction when it shall be desired to 95 ventilate the interior of the device. It will be observed that the glass will be held not only by the clamping action of the side members 15 but also by direct engagement with the resilient clamp 24, the intermediate portion of which will be bent or arched in a downward direction in engagement with the top-most face of the glass as will be seen most clearly in Figs. 1 and 4 of the drawings.

It is obvious that in connection with the 105 side members 15 of a standard size, back and front members 16, 17 of different widths may be used, thus enabling the side walls to be utilized in the construction of protectors of different size and capacity.

From the foregoing description, taken in connection with the drawing hereto annexed, it will be seen that I have produced a very simple and inexpensive device of its kind which may be conveniently knocked down or disassembled for convenience in shipping or storing the same and which, when assembled, may be readily placed on the ground over the plant that is to be protected and forced, the transparent front member being exposed toward the sun or otherwise, according to circumstances and the needs of the plant.

Having thus described the invention, 15 what is claimed as new is:

1. A plant protecting and forcing device comprising triangular side members each having a dove-tailed groove adjacent to its back edge and a groove adjacent to its front edge, in combination with a back member having dove-tailed tongues engaging the

dove-tailed grooves, and a transparent front member adjustably supported in the grooves adjacent to the front edges of the side members, and a wire clamp extending across the 25 front member in engagement therewith to retain it in adjusted position and having downturned arms provided with terminal prongs engaging the side members.

2. In a plant protecting and forcing device, a pair of side members having inclined front edges and longitudinal grooves adjacent thereto and a transparent front member adjustably supported in said grooves, in combination with a resilient 35 clamp having down-turned arms provided with terminal prongs engaging the side members, said clamp being intermediately arched downwardly in engagement with the transparent front member.

In testimony whereof I affix my signature.
FRANK C. LORENCE.
